UNITED STATES PATENT OFFICE

FRANCIS E. MEYER, OF PHILADELPHIA, PENNSYLVANIA, ASSIGNOR TO THEO. ALTENEDER & SONS, OF PHILADELPHIA, PENNSYLVANIA, A CORPORATION OF PENNSYLVANIA

INKSTAND

Application filed October 3, 1929. Serial No. 397,065.

This invention relates to inkstands and more particularly to improvements upon inkstands of the type disclosed in Patent No. 825,691, issued to F. A. Alteneder July 5 10, 1906.

Inkstands of the general class disclosed in that patent are arranged to enable a draftsman to fill or charge a pen with ink by a single handed operation. While being rather 10 effective for the purpose it has been found in practice that such inkstands as previously constructed are possessed of certain disadvantages militating against their universal use. The principal objectionable features might 15 be summarized as evaporation, varying ink charge and lack of adjustability generally.

Among the objects of this invention are: to obviate the disadvantages of earlier constructions of inkstands; to improve the construction of inkstands; to provide an inkstand, having means for recharging pens, with an effective sealing device to preclude the evaporation of ink; to provide an inkstand with an improved receptacle or bottle 20 arranged to facilitate the recharging of pens without appreciable loss from evaporation; to provide an inkstand for recharging pens in which the charge of ink is uniform in quantity regardless substantially of the level 25 of the ink in the container; to provide an inkstand with means for centering the ink container with relation to the charging device by a single handed operation; to reduce the costs of manufacturing inkstands; and many 30 other objects and advantages as will become 35 more apparent as the description proceeds.

In the accompanying drawings:

Fig. 1, represents a vertical section through an assembled inkstand according to this invention, and

Fig. 2, represents a top plan thereof.

The invention includes a base 10, having an upper recess 11, of a diameter slightly but appreciably greater than the diameter of the bottle 12, arranged for laterally adjustable seating in the recess 11. This is in contrast to previous practice in that the recess was just of sufficient area as to receive the base of a bottle without any possible lateral adjustment such as may be required of such bottles

to allow for variations in size and contour. Centrally of the base and in close proximity to the periphery of the recess 11, a vertically upstanding lug 13 is provided, the upper plane surface of which is cut away as at 14 to 55 seat the inner end of the spring clevis, clamp or yoke 15, the legs of which straddle, and bear resiliently upon, the constricted portion 16 of the bottle 12. The resilient clamp 15 is adjustably fastened to the stop 13, by the bolt 60 or hand screw 17, having the knurled end or head 18 extending upwardly into a convenient position for gripping by the operator, so as to vary the tension of the spring fingers 65 upon the bottle, with ease and facility.

The rear portion of the stop 13 carries the horizontally spaced ears 20, between and with relation to which the lever arm 21 is arranged to pivot by means of a pin 22 passing through the ears 20. The lever arm 21 70 at its lower end carries the laterally offset handle 23. At its forward end the lever arm 21 is enlarged as at 24 to a diameter appreciably larger than the mouth of the bottle. The lower face of the enlargement 24 is 75 substantially plane, as at 25, and is axially drilled and threaded as at 26 to receive the substantially vertical threaded shank or stem 27, which carries at its upper end the knurled head 28. The upper portion of the enlargement 24 has a vertical annular recess 30, concentric with the drilled opening 26, terminating in a square shoulder 31 at the bottom, and arranged to receive a compressible washer 32 and an internally threaded lock nut 33. 80 The lock nut has a knurled enlargement 34, and is arranged to threadably engage the threaded shank or stem 27. Locking movement of the nut 33 frictionally engages the threaded shank and holds same against movement, as will be clear, but also compresses 85 and distorts the washer 32 into substantially air-tight engagement with the threads of the shank 27, to preclude evaporation.

The upper portion of the bottle 12 includes 90 the restricted neck 9 and the outwardly tapered or flared conical mouth 19. In order to effect a tight seal for the mouth of the bottle, but one which is easily broken upon manipulation of the lever 21, a removable 100

and, obviously, renewable closure element is provided. The closure is preferably comprised of an outer shell of substantially dish-shaped construction including an outwardly tapered annular wall 35, merging into an integral plane surfaced apertured disc 36, having a more or less yielding sealing element 37 engaged in the shell, the inner periphery of which is tapered as at 38 to 5 form an inverted conical seal to cooperate with and seat upon the outward taper or conical mouth 19, of the bottle, to provide a sealing connection. The connection is substantially air-tight for the length of the outward surface of said flare, and it is noteworthy, that the arc of movement of the closure on the pivotal pin 21 of the lever arm is closer to the vertical than a line of the surface 38, so that pivotal movement of the lever 10 arm has no binding or frictional effect on the mouth of the bottle. There is, therefore, no contacting sealing element in registry with the aperture or mouth opening of the bottle as such might prevent seating engagement 15 of the conical elements. It is to be observed that clearance, as at 40, is provided between the upper edge of the bottle and the disc portion of the closure to allow for wear to insure a proper and complete seating of 20 the closure on the bottle.

While it will be obvious that the construction and material of the closure element may be of any desired sort, yet for illustrative purposes it may be mentioned that the preferred material is a fairly hard or resilient rubber composition, vulcanized into the shell described. This has long life, is wear resistant and effects a shock absorbing function when the lever is released and descends 25 upon the bottle by gravity. It will be understood that the shell with the vulcanized sealing element attached therein is removably attached to the lower plane face 25 of the enlargement 24 of the arm, as by means 30 of screws 41.

In order to simplify the construction of the quill or ink conveying portion of the device, it is preferred that the threads on shank 27 be carried to the end of the shank or stem 35 and that a filler of twisted wire or the like, as 42, be provided, the upper portion of which, as at 43, comprises a helical coil arranged for threaded engagement on the threaded shank 27. This engagement is 40 sufficiently tight as to cause the filler element to remain in a given position, but yet such as permits its angular disposition to be varied as desired.

It will be obvious that inevitably there will 45 be variations between given bottles, or between a pair of closure elements which might cause a greater or less degree of eccentricity of the parts such as might preclude sealing closure of the bottle. For this reason means 50 are provided to facilitate proper registration

of the elements by providing a variable tension on the fingers arranged to hold the bottle, and the enlarged recess permitting lateral adjustments of the bottle on the base, as well as the peculiar relation of closure and bottle mouth whereby a centering of the bottle is had by simply moving the closure down on the bottle.

The initial positioning of the bottle 12 in its recess 11, in concentric centered relation to the closure element on the lever arm may be accomplished with facility simply retracting the screw 18 to relieve the pressure on the fingers of the yoke, dropping the closure element on the bottle mouth to slide it laterally to concentric seating alignment with the closure and tighten screw 18 when the bottle is properly located. With the improved closure disclosed, it will be understood that slight variations in the castings or in the construction or attachment of the shell of the closure need not make any difference in the proper disposition of the parts, inasmuch as dropping the lever arm until the closure engages the mouth of the bottle, with the pressure removed from the spring fingers, as will be clear, centers the bottle in its exactly proper place, and, moreover, this centering engagement is such as to maintain the centered relation during the time of tightening bolt 18, in order to impart locking pressure to the fingers of the yoke.

It will be obvious that the level of ink in the bottle will vary from time to time, and that it is desirable that the stem or shank be vertically adjusted, so as to insure that the filler or quill contain the same amount of ink, substantially, at each charging movement. It will be understood that it is a simple one 100 handed operation to back off the lock nut 33 to a degree sufficient to permit rotation of the threaded shank in the desired direction to raise or lower the filler 42, after which the lock nut 34 may be twisted down upon the threaded shank so as to abut and compress 105 the washer 32 into tight engagement with the threads on shank 37. It will be understood, moreover, that such manipulations and the continued use of the inkstand will be accomplished with a minimum of evaporation as 110 an air-tight assembly is provided by means of the compressible washer 32.

The operation of the device will be quite clear, it being simply noted that there is nothing in the assembly of closure and bottle mouth which can prevent the instantaneous vertical separation of the parts, and yet when the hand is removed from handle 23, the closure, through gravity alone, effects an absolutely air-tight seal with the flared conical mouth of the bottle. Obviously if desired resilient or other means (not shown) may be used to draw or hold the closure in sealing contact with the bottle mouth.

It is of interest, moreover, to note that the 125

closure upon which most of the wear takes place, is capable of replacement at a minimum of expense, so as to render the life of the entire device of indefinite but protracted duration.

5 I claim as my invention:

1. In an inkstand, a base arranged to receive an ink reservoir, means for adjustably engaging such reservoir to hold it to the base, a closure element, means for moving the closure element in a fixed predetermined path transverse to said base, the closure element including a conical surface arranged to frictionally engage the mouth of such reservoir to laterally adjust such reservoir to a position of substantial concentricity with the closure element, and a quill operatively associated with the closure element.

10 2. In an inkstand in combination, a base, a receptacle mounted on the base and having a restricted mouth, an arm pivoted to the base, a closure mounted on the arm and arranged to engage upon and seal the mouth of said receptacle, a charging quill mounted on the arm and extending into said receptacle, and means for vertically adjusting the quill relative the arm in accordance with variations in the level of ink in the receptacle.

15 3. In an inkstand in combination, a base, a receptacle mounted on the base and having a restricted mouth, an arm pivoted to the base, a closure mounted on the arm and arranged to engage upon and seal the mouth of said receptacle, a charging quill mounted on the arm and extending into said receptacle, and means for vertically adjusting the quill relative the arm in accordance with variations in the level of liquid in the container, said means including a compressible washer arranged to bear against said quill to prevent leakage of air along said quill.

20 4. In an inkstand in combination, a base having a shallow depression, a bottle of smaller diameter than said depression and arranged to seat therein, a lever arm pivotally mounted on said base, a closure element carried by said lever and having an internally recessed bottle engaging surface arranged to engage said bottle and to adjust it laterally in the recess so that it is substantially concentric with said closure, and resilient means for clamping the bottle against movement in the recess to maintain the adjusted position.

25 5. In an inkstand in combination, a support, a bottle having a conical mouth, a lever arm pivoted to the support, a closure removably mounted on said lever arm and comprised of a shell of metal and a lining secured to the shell, the lining having an inner periphery of inverted conical shape and arranged to seat upon the conical mouth of the bottle, the sealing connection between the closure and the mouth being substantially airtight under the influence of gravity so as to preclude evaporation, but so arranged as to

be instantaneously broken upon vertical arcuate movement of the closure away from the bottle.

6. In an inkstand in combination, a base, a lever arm pivoted thereto and having a vertical threaded opening and a concentric recess, a shank threadably mounted in the threaded opening and carrying a quill, a washer in the recess and an internally threaded lock washer slidably mounted in the recess to compressing engagement with the washer to provide for vertical adjustment of the shank while precluding the passage of air along the threads thereof.

7. In an inkstand, a base arranged to receive an ink reservoir, an arm pivotally mounted on the base, a closure element carried by the arm, the closure element including a conical surface arranged to frictionally engage the mouth of such reservoir to secure relative lateral adjustment between the closure element and such reservoir to such relative positioning as will establish concentricity of the closure element and such reservoir, and a quill operatively associated with the closure element.

Signed at Philadelphia, county of Philadelphia, and State of Pennsylvania, this 5th day of Aug., 1929.
